GARMENT

Franklin Chatfield, Minneapolis, Minn., assignor
to The Munsingwear Corporation, Minneapolis,
Minn., a corporation of Minnesota

Application May 25, 1935, Serial No. 23,396

5 Claims. (Cl. 2-224)

This invention relates to new and useful improvements in garments of the general type having fly openings, and an object of the invention is to provide an improved buttonless fly opening which is particularly applicable for snug fitting garments, as it will not gap open, although it may be used in all types of garments requiring a fly opening.

A further object is to provide an under garment having a fly opening, one edge of which is substantially vertically disposed, and the other edge of which is disposed at an incline, thereby to prevent the fly opening from opening when the garment is worn.

15 A further object is to provide a garment comprising a body portion having an insert in the front portion thereof, one edge of which extends upwardly at an incline from a point above the crotch, and is unsecured, and a second insert overlying a portion of said first mentioned insert and having one edge portion substantially vertically disposed and cooperating with said inclined unsecured edge to provide a fly opening for the garment.

25 The outstanding feature of the invention thereof is to provide a buttonless, non-gapping fly opening which may be manufactured at small cost, and may readily be embodied in all types of garments requiring a fly opening.

30 Other objects of the invention will appear from the following description and accompanying drawing and will be pointed out in the annexed claims.

In the drawing there has been disclosed a structure designed to carry out the various objects of the invention, but it is to be understood that the invention is not confined to the exact features shown as various changes may be made within the scope of the claims which follow.

40 In the drawing:

Figure 1 is a front view of a garment showing the invention embodied in the construction thereof;

45 Figure 2 is a similar view, partially broken away, to show the unsecured inclined edge of the insert which provides the concealed edge of the fly opening;

Figure 3 is a fragmentary view showing the fly opening partially open; and

50 Figure 4 is a view showing a fly opening of slightly modified construction.

In the selected embodiment of the invention here shown, for purposes of disclosure, there is illustrated in Figures 1 and 2, a garment comprising a body portion 2, preferably provided at its

upper portion with an elastic waist band 3, and having suitable leg openings 4.

An important feature of the invention resides in the unique construction of the fly opening provided in the front of the garment, which is so constructed that it cannot gap or open, even though the material constituting the body of the garment is subjected to tension, as in a snug or close fitting garment.

To construct the novel fly opening herein disclosed, an insert 5 is preferably embodied in the construction of the front of the garment and has one of its upright edges secured to the body of the garment by suitable stitching 6. The insert 5 is preferably shaped as best shown in Figure 2, 15 wherein it will be noted that the lower right hand corner thereof, when viewed as shown in the above figure, is cut off, thereby to provide an inclined edge 7 which constitutes the inner edge of the fly opening. The edge 7 is reinforced in the usual manner by a suitable hem to prevent the material from raveling. The upper right hand edge portion of the insert 5 is secured to the body of the garment by stitching 8, and its upper edge may be suitably secured in place by stitching 9, 20 which also secures the waist band 3 to the body of the garment. The lower portion of the insert 5 is secured to the crotch portion 10 of the garment by stitching 11.

A second insert 12 overlies a portion of the insert 5 and has its right edge portion secured to the body of the garment by the stitching 8, which extends from the waist band 3 to the leg opening 4, at the right hand side of the garment, when viewed as shown in Figures 1 and 2. The upper edge of the insert 12 is secured by the stitching 9 and the lower portion thereof by the stitching 11. 30

The insert 12 is shown relatively narrower in width than the insert 5, and has a vertically disposed edge 13 which extends upwardly from a point above the crotch to the waist band 3, at the upper portion of the garment. The upper portion of the insert 12 is secured to the insert 5 at the center of the garment, by suitable stitching 14 and 15, as shown in Figures 1 and 2, whereby the lower portion of the edge 13 of the insert 12 is unfastened, and provides the outer edge of the fly opening. By thus arranging the inserts 5 and 12 in overlapping relation, and leaving the edge portions 7 and 13 unsecured, a fly opening 40 is provided which will always remain closed, regardless of body movements and postures.

A fly opening constructed in accordance with the invention herein disclosed, cannot readily open, when the garment is in use, because of the 45 50 55

unique arrangement of the inclined inner edge 7, which, because of being disposed in the particular manner shown and described, is always maintained substantially taut, and will therefore lie smoothly against the body. Also, because of the inclined unsecured edge 7 of the insert 5 extending from a point above the crotch to the seam 8 at the side of the garment, and having its upper end terminating substantially in horizontal alignment with the lower row of stitches 15, any tension imparted to the body of the garment will tend to close the fly opening, rather than open it, which is a very desirable feature in garments of this general character.

15 Constructing the fly opening by means of inserts secured to the front of the garment, as herein set forth, does not increase the cost of manufacture, as compared to garments having fly openings of ordinary construction. The improved fly opening provided, also does not require buttons or other fastening means for keeping it closed. The inserts 5 and 12, in addition to providing an improved fly opening, also strengthen the front of the garment, without causing it to become bulky 25 and uncomfortable to wear.

The fly opening extends from the seam 11 to the row of stitches 15, clearly shown in Figures 1 and 2, and because of the lower edge of the inner edge 7 thereof terminating adjacent to the center of the garment, but beneath the outer edge 13, it may be readily and conveniently opened, as illustrated in Figure 3.

In the drawing, I have shown inserts 5 and 12 embodied in the front of the garment to provide 35 the fly opening. It is to be understood, however, that I do not wish to be so limited, as the fly opening might be constructed without the use of the inserts 5 and 12, by simply overlapping portions of the material constituting the body of 40 the garment in a manner to provide the inner inclined edge 7 and the outer edge 13.

In Figure 4, there is shown the front of a garment in which inserts 16 and 17 cooperate to provide the fly opening. These inserts are substantially alike in configuration, with the exception that one is right hand and the other left hand. The upright outer edges of the two inserts are secured to the body of the garment by stitching 18, and their upper horizontal edges are 50 secured to the waist band 3 by the seam 9. The lower edges of the inserts 16 and 17 are secured to the crotch portion 10 of the garment by the stitching 11.

In the form shown in Figure 4, it will be noted 55 that the inserts 16 and 17 are provided with inclined edges 19 and 20, respectively, which cooperate to provide the edges of the fly opening. The two inserts are arranged in overlapping relation, as shown, and the edges 19 and 20 thereof are unsecured, whereby the fly opening may readily be opened in substantially the same manner as shown and described with reference to the previous figures.

The form shown in Figure 4 is comparatively 60 simple in construction and does not require any stitching at the top central portion of the garment, as shown by the numerals 14 and 15 in Figure 1. The inserts 16 and 17 are overlapped in substantially the same manner as the inserts 5 and 12, shown in Figures 1 and 2, and, in addition to providing the fly opening, also reinforce and strengthen the front of the garment. It will also be noted that a fly opening constructed as shown in Figure 4, will always remain closed, 70 when the garment is worn, because any tension

applied to the fabric or material from which the garment is constructed, will tend to close the fly opening rather than open it. It is to be understood that the fly opening shown in Figure 4 may be constructed without the use of inserts, by 5 simply bringing the side portions of the body of the garment together at the front thereof and overlapping them and securing them together in substantially the same manner as the inserts 16 and 17. When thus constructed, the overlapped 10 portions of the material are provided with inclined edges corresponding to the inclined edges 19 and 20 of the inserts 16 and 17.

I claim as my invention:

1. In a garment of the character described a 15 body portion having a crotch and leg openings, and overlapping front sections extending upwardly from a point above the crotch to the waist line of the garment, said front sections being stitched together along their top edges and along 20 their bottom edges, the overlying front section having an upwardly extending side edge, the upper portion of said edge being stitched to the underlying section and the lower portion of said edge being free, the underlying front section having a free edge portion extending diagonally upward opposite the free side edge portion of the overlying section to a point opposite the bottom of the stitching along the upper side edge portion of the overlying section, the edge of the 25 upper part of the underlying section above the free diagonal edge portion being stitched to the overlying section, the respective free edge portions of the overlapping sections defining a concealed fly opening.

2. In a garment of the character described, a body portion having a crotch and leg openings, and overlapping front sections extending from a point above the crotch to the waist line of the garment, said sections being stitched together 40 along their top edges and their bottom edges, the overlying section having a vertical edge portion located substantially medially of the front of the garment above the crotch, the underlying section extending well beyond the middle of the garment and terminating above one of the leg openings, stitching connecting the inner end of the underlying section to the overlying section, a concealed inclined side edge portion on the underlying section extending downwardly and inwardly from the terminal end of the underlying section to meet the stitching along the bottom ends of the sections close to the vertical edge of the overlying section, the inclined edge portion of the underlying section and the opposing lower 55 vertical side edge portion of the overlying section being unsecured and defining a concealed fly opening.

3. In a garment of the class described, a body portion having a crotch, leg openings and overlapping front sections, a waist band at the upper end of the body portion, said overlapping front sections extending from the waist band to a point above the crotch, one of said front sections terminating in a vertical edge located substantially medially of the front of the garment above the crotch, the second front section extending well across the front of the garment beyond the vertical edge of the first section and in its upper area at and adjacent the waist band making a 65 wide area of overlap with the first section, stitching securing the upper overlapping areas of the front sections together but leaving the lower portion of the vertical edge of the first section free, an inwardly and downwardly inclined free 70

edge portion on the second section forming with the free lower vertical edge portion of the first section a substantially triangular free lower area of overlap between the sections and providing 5 a concealed fly opening, and stitching securing together the lower ends of the front sections.

4. In a garment of the class described, a main body portion having a crotch and leg openings, a continuous circumferential waist band at the 10 upper end of the body portion, overlapping sections in the front of the garment supported by and extending downwardly from the waist band to a point above the crotch, the overlying front section terminating in a vertical edge located 15 substantially medially of the front of the garment above the crotch, the underlying front section extending well across the front of the garment beyond the vertical edge of the overlying section, a vertical edge on the underlying section in the 20 upper area of overlap, means securing the sections together in their upper area of overlap but leaving said sections free in their lower area of overlap, and an inclined free edge portion on the underlying section extending downwardly 25 from the lower end of the vertical edge of said section and inwardly to meet the bottom of said section adjacent the lower end of the vertical edge of the overlying section, the sections being secured together at the meeting point of the 30 vertical and inclined edge portions of the underlying section.

5. In a garment of the class described, a main body portion having a crotch and leg openings, a waist band at the upper end of the body portion, said body portion constituting the rear portion of the garment and including portions extending beyond the sides into the front, overlapping front panels seamed to the respective side edges of said extending portions supported by and extending downwardly from the waist band to a point above the crotch, the overlying 10 front panel terminating in a vertical edge located substantially medially of the garment above the crotch, the underlying front section extending well across the front of the garment beyond the vertical edge of the overlapping section and in its upper area at and adjacent the 15 waist band making a wide area of overlap with the overlying section, an inclined free edge portion on the underlying section extending downwardly from the wide upper area of overlap and 20 inwardly to meet the bottom of said section adjacent the lower end of the vertical edge of the overlying section, the vertical edge of the overlying section in the lower area of overlap opposite the inclined edge portion of the underlying section being free and forming with said inclined edge portion a substantially triangular concealed 25 fly opening, and means above the fly opening joining the overlapping sections in their upper wide area of overlap. 30

FRANKLIN CHATFIELD.
